Patented Nov. 4, 1919.

Inventor:

John B. Marshall,

by James F. Duhamel,

Attorney.

UNITED STATES PATENT OFFICE.

JOHN B. MARSHALL, OF NEW YORK, N. Y.

DESIGN FOR A BADGE OR SIMILAR ARTICLE.

54,106.

Specification for Design.

Patented Nov. 4, 1919.

Application filed May 13, 1919. Serial No. 296,943. Term of patent 14 years.

To all whom it may concern:

Be it known that I, JOHN B. MARSHALL, a citizen of the United States, and residing at New York, New York county, New York State, have invented a certain new, original, and ornamental Design for Badges or Similar Articles, of which the following is a specification, reference being had to the accompanying drawing, forming a part thereof.

The figure illustrates a face view of a badge showing my new design.

I claim:

The ornamental design for a badge or similar article, as shown.

In testimony whereof, I have signed my name to this specification in the presence of two subscribing witnesses, this eighteenth day of April, 1919.

JOHN B. MARSHALL.

Witnesses:

JAMES F. DUHAMEL,
THEO. H. FRIEND, Jr.
